UNITED STATES PATENT OFFICE.

ARTHUR D. DAYTON, OF LOS ANGELES, CALIFORNIA.

PROCESS OF BOOKBINDING.

Application filed November 19, 1924. Serial No. 750,941.

To all whom it may concern:

Be it known that I, ARTHUR D. DAYTON, a citizen of the United States, residing at Los Angeles, in the county of Los Angeles and State of California, have invented certain new and useful Improvements in Processes of Bookbinding, of which the following is a specification.

This invention relates to a novel process for binding the signatures or sections of a book together and has for its primary object to provide novel means whereby the entire book can be handled as a unit during the binding process instead of handling each signature or section independently.

Another object of the invention is to provide a novel book binding process which will simplify the art of book binding and effectively decrease the cost and time of making a book and the necessity of employing complicated machinery for making and uniting the sections or signatures.

A further object of the invention is the provision of novel means for uniting the sections or signatures of a book together, which consists in aligning the sections or signatures together and forming diagonally extending slits in the back of the book unit for receiving binding threads or cords in counterdistinction to forming incisions straight across the back of the book for receiving the cords, the diagonal incisions with the binding cords permitting the book to be easily rounded and backed and allowing the strain on the threads or cords to be diffused over a large area of the book back thereby allowing the book to be opened easily and without disclosing to view unsightly holes.

A further object of the invention is the provision of novel means for anchoring the binding cords or threads in the incisions and the connection of the signatures or sections together by a special adhesive and novel means for holding the terminals of the threads or cords in place.

A further object of the invention is to provide novel means for securing the end sheets or fly leaves in place for insuring the proper anchoring of the terminals of the binding cords or threads in place and the proper connection of the book unit or signatures with the book back.

A further object of the invention is to provide a book which will be simple and easy to manufacture, one that will be dura-

ble and efficient in use, and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings,

Figure 1 is a front elevation of a book section illustrating the various steps in the binding process,

Figure 2 is a rear elevation of the book unit showing the various steps in binding process,

Figure 3 is a transverse section through the book unit taken on the line 3—3 of Figure 1 looking in the direction of the arrows showing the book sections or signatures bound together and the method of applying the end sections or fly leaves in place,

Figure 4 is a side elevation of the book showing the signatures or sections united and the book unit placed in a book back, the back being shown broken away and in section,

Figure 5 is a rear elevation of the complete book showing the back thereof broken away to illustrate the sections or signatures in their complete bound condition,

Figure 6 is a detail section taken through the complete book taken on the line 6—6 of Figure 4 looking in the direction of the arrows.

Referring to the drawings in detail, wherein similar reference characters designate corresponding parts throughout the several views the letter A generally indicates a hook constructed in accordance with my improved process. The book A includes a plurality of book sections or signatures 10 which are bound together in accordance with my invention, which will now be described, to form a complete book unit after which the same is applied to a conventional cover 11.

The improved method or process of constructing the book permits all of the sections or signatures to be handled as a single unit, eliminating the necessity of handling the sections or signatures separately.

In carrying out the invention all of the book sections or signatures 10 are placed one upon the other in proper sequence and lined up by any suitable means such as

placing a weight on the sections or signatures opposite to the back thereof. After the sections or signatures have been properly aligned up the back edge of the book unit 5 is coated with a specially prepared adhesive compound which is left to dry. A series of equi-distantly spaced incisions are cut diagonally across the back of the book section as clearly shown in Figures 1, 2 and 5. 10 These incisions are indicated by the reference character 12 and are preferably formed about three-sixteenths of an inch deep and approximately three-quarters of an inch apart. Of course the depth of the incisions and the distance apart of the incisions can be varied according to the different kinds of books being made.

A strong cord or thread is then inserted in each incision to the full depth thereof and 20 the ends of the threads or cords are allowed to project over the sides of the book sections approximately one-half of an inch. The terminals of the cords projecting over the sides of the book unit are drawn down along 25 the sides of the book sections at the back edges thereof at right angles to the incisions 12 after which a coating of paste or other adhesive is then applied to the sides of the book at the back thereof and the ends of 30 the threads or cords. A heavy coating of especially prepared adhesive is applied to the back of the book prior to the fastening of the cord terminals and is worked well into the incisions so as to firmly anchor the cords 35 or threads in place and to effectively unite the book sections or signatures 10.

It is to be also noted at this point that the incisions 12 not only extend diagonally across the back of the book section, but that 40 the same extend inwardly at an angle of substantially forty-five degrees to the back of the book as indicated by the reference character 14 in Figure 1 of the drawing.

The means of securing the cord or thread 45 terminals in place is clearly shown at 15 in Figure 1 of the drawings.

After the paste and the specially prepared adhesive has become thoroughly dried the sections or signatures 10 will be firmly 50 bound together forming a complete unit and the novel end or fly leaves 16, which will now be described, can be connected to the book section.

Each end section includes an inner single 55 sheet 17 and an outer folded sheet 18. A strip of cloth 19 is utilized for connecting the sheets 17 and 18 together and as shown in Figures 1 and 6 of the drawings the fabric strip is secured about the folded edge 60 of the double sheet 18 as at 20 and then secured to the outer face of the inner sheet 17 at the rear edge thereof as at 21. The strip is now folded back upon itself as shown in Figure 6. The section 16 can be applied to 65 the complete section after the paste has been

applied to the terminals of the threads or cords 15 and suitable weights are placed upon the book until the paste is dry. The completed book section is now placed in the cover 11 and connected thereto in the conventional way. 70

I lay particular stress upon the incisions or kerfs 12 in the back of the book and the means of securing the terminals of the binding cords or threads 13 in place by the end 75 sections. The cords laid in the diagonally extending kerfs or incisions 12 permit the strain on the cords to be distributed over a relatively wide area and permit the book to be easily opened besides firmly holding the 80 sections or signatures in place.

Changes as to details may be made without departing from the spirit or the scope of this invention, but:—

What I claim as new is:—

1. In the method of binding book signatures together consisting in aligning the book signatures to form a book unit cutting diagonally extending kerfs in the back of the book unit and anchoring binding cords in 90 the kerfs.

2. That step in the method of forming a book which consists in aligning the book signatures together to form a unit, cutting kerfs in the book diagonally across the back 95 thereof and at an angle to the side edges of the book and anchoring binding cords in said kerfs.

3. The method of binding book signatures together which consists in first aligning the book signatures, cutting kerfs across the back of the aligned book signatures, applying an adhesive to the back of the book signatures, placing binding cords in the kerfs, applying a second coating of adhesive to the back of the signatures and in said kerfs around the cords drawing the terminals of the cords down the sides of a book section formed by said aligned book signatures parallel to the back edges of the book and securing the terminals in place by an adhesive. 105

4. The method of forming a book which consists in aligning the book signatures to form a book section applying a coating of adhesive to the back of the book section, forming diagonally extending kerfs across the back of the book section, placing binding cords in the kerfs in engagement with the lower walls thereof, applying a second coating of adhesive to the back of the book section and in said kerfs around the cords, drawing the terminals of the cords down the sides of the book section in parallel relation to the back edge of the book section, applying a coat of adhesive to the sides of the book section at the rear edge over said cords and placing end sections of the book over the terminals of the cords and the pasted area. 115

5. The method of forming a book which consists in taking a plurality of book signatures and aligning the same together to form a book section having diagonally extending kerfs across the back of the book section at an angle to the ends of the book section, applying a coat of adhesive to the back of the book section placing binding cords in the kerfs, applying a second coat 10 of adhesive to the back of the book and in said kerfs, drawing the terminals of the cords down the sides of the book and securing the same in place by an adhesive, applying end sections to the main book section 15 which consists in a single sheet and a double sheet connected by binding cloth.

6. A book including a plurality of book signatures having kerfs extending diagonally across the back thereof and binding 20 cords anchored in said kerfs.

7. A book including a plurality of signatures placed together in proper alignment having kerfs extending diagonally across the same at the back thereof, said kerfs

extending inwardly at an angle to the sides 25 of the book signatures, binding cords in said kerfs having the terminals thereof secured to the sides of the book section formed by said signatures in parallel relation to the backs of said signatures.

8. In a book including a plurality of signatures disposed in proper alignment having a plurality of equi-distantly spaced kerfs extending diagonally across the back 30 thereof, cords anchored in said kerfs having the terminals thereof anchored to the sides of the book section formed by said signatures in parallel relation to the rear edges thereof and end sections disposed over said 35 cord terminals including an inner sheet and an outer folded sheet and a binding cloth secured about the folded edge of the folded sheet and secured to the outer face of the single sheet at the rear edge thereof.

In testimony whereof I affix my signature. 40

ARTHUR D. DAYTON.
